UNITED STATES PATENT OFFICE

HARRISON O. BLAISDELL, OF BROOKLYN, NEW YORK, ASSIGNOR TO UNDERWOOD
ELLIOTT FISHER COMPANY, OF NEW YORK, N. Y., A CORPORATION OF DELAWARE

TYPEWRITING MACHINE

Application filed October 11, 1927. Serial No. 225,450.

The present invention relates to devices for inserting and gaging work-sheets to typing position at the front of a typewriter-platen. It may be advantageously applied to book-keeping machines for making a condensed record of statement-sheets.

This invention relates to typewriting machines, and more particularly front-insertion devices used therefor. In the present invention there is provided a paper-table at the front of the platen, which, when in one position, will aid in the insertion of a work-sheet downwardly into the typewriter at the front thereof. The top edge of the sheet is fed down below a pair of normally disappearing pins mounted at the front of the typewriter, after which the table is pressed down a short distance so that the pins protrude therethrough, and the inserted work-sheet is pulled up against the pins for the purpose of aligning and collating the sheet with respect to the record-sheet. The work-sheet then being in position, the table is swung about its pivot to lie close against the platen. The swinging of this paper-table to its other position enables an operator to see the typing line clearly while typing, and also to hold the work-sheet against the platen and guide the same during line-spacing and prevent it from falling forward.

Another feature of the invention is that, during the swinging motion of the paper-table, the feed-rolls are either moved to their effective or ineffective position so that, after having typed a sheet, the paper-table is swung forward, thereby releasing the feed-rolls, and the typed sheet removed and a fresh sheet quickly inserted at the front and aligned against the aligning pins, after which the paper-table is swung back against the platen, simultaneously restoring the feed-rolls.

In carrying out my invention, there is provided at the front of the platen a slotted paper-table pivotally mounted on the opposite sides of the carriage. A plate mounted on the carriage-rail supports the table in a forwardly-inclined sheet-inserting position, slightly above its extreme forward position, for inserting a statement-sheet and under-

lying carbon over the top of the downwardly-inclined table between a record-sheet previously fed around the platen from the rear, and a usual front apron of a rear paper-table, a fixed deflector-plate being disposed between the bottom edge of the pivoted paper-table and the top edge of the apron. An operative connection between the table and the usual lower feed-roll is effective for releasing the feed-rolls when the paper-table is disposed in its sheet-inserting position. After the statement-sheet has been inserted around the platen, the table may be easily pushed down to its extreme forward position by pressure of the operative's fingers, while still gripping the leading-end of the statement-sheet. Upon the last-named movement of the paper-table two gage-pins, which are mounted on the plate on the front rail of the carriage, project upwardly through the slots in the paper-table. By pulling the leading edge of the statement-sheet up against the gage-pins, and gaging its right-hand side edge against a side-edge gage fast on the paper-table, the first writing line of the statement-sheet is positioned to be subsequently disposed at the printing line of the platen, and the statement-sheet is collated with respect to the record-sheet. Then, while the operative grips the statement-sheet against the pivoted paper-table, the latter is swung to its rearmost position, which brings its lower edge above the printing line and out of the paths of usual types moving to strike against the platen. Upon rearward movement of the paper-table the above-noted connection between the table and the lower feed-rolls causes the latter to be made effective.

A feature of the present invention resides in an arrangement of the operative connection between the pivoted paper-table and the lower feed-rolls whereby the connection is released when the paper-table is in its rearmost position, the feed-rolls being left free for operation by the usual feed-roll release lever independently of the paper-table.

Another feature resides in the provision of means for inserting wide statement-sheets from the forwardly inclined paper-table without colliding with the usual type-guide.

These means include making the fixed deflector-plate substantially as long as the platen and positioning the plate at one side of the printing point with its top edge disposed as high as possible without interfering with the lateral movement of the side bars of the carriage-frame. The platen will be moved alongside the deflector-plate for inserting the statement-sheet at one side of the type-guide.

Another feature is the provision of means mounted on the forward side of the pivoted paper-table for engaging a plate carrying the gage-pins and yieldingly holding the paper-table in its work-sheet feeding position above the pins.

Other features and advantages will herein-after appear.

In the accompanying drawings,

20 Figure 1 is a partial top plan view of the carriage of an Underwood typewriting machine having my invention applied thereto. Certain other parts of the machine, which co-operate with the carriage, are shown in 25 this view.

Figure 2 is a fragmentary vertical sectional view along the line 2—2 of Figure 1.

30 Figure 3 is a fragmentary cross-sectional view, front to rear, of the mechanism shown in Figure 1, the collating table being shown in its extreme forward position, wherein gage-pins are made effective for gaging a work-sheet on the front paper-table.

Figure 4 is a view similar to Figure 3, the 35 collating table being shown in its rearmost position guiding a statement-sheet rearwardly at the delivery side of the platen.

Figure 5 is an isometric view, shown partly broken away, of the parts illustrated in Fig- 40 ure 1.

Figure 6 is a fragmentary isometric view, illustrating the construction at the right end of the platen for releasing the feed-rolls upon forward movement of the collating table.

45 Figure 7 is a diagrammatic view of a carriage of an Underwood typewriting machine having my invention applied thereto, the carriage being shown disposed in its extreme rightmost position for co-operation with the 50 deflector-plate mounted at the right of the printing point for inserting a work-sheet at the front of the platen from the forwardly-inclined front paper-table without fouling the type-guide.

55 In an Underwood billing typewriting machine, types 10 strike against a platen 11 on a platen-shaft 12 journaled in sides 13 of a platen-frame 14. A carriage 15 has side bars 16 and a front rail 17, the latter disposed 60 forwardly from the platen. A segment 18 is fastened rigidly on the main frame members 18^a and carries a type-guide 19. A paper-table 20 extends between the sides 16 of the platen-frame at the receiving side of the 65 platen and has a forwardly-extending apron

21 which is provided with cutouts through which front feed-rolls 22 and rear feed-rolls 23 may engage against the bottom side of the platen. To release the feed-rolls, i. e., swing them away from the platen, a cross-rod 24 extends between the sides of the platen-frame 14 and serves as a fulcrum for a pair of lever-arms 25 and 26, which are spring-pressed toward the platen and have their outer ends arranged for supporting axles of the feed-rolls. The arms 25 and 26 have integral, depending extensions 27, 28 which engage against the rear and front sides respectively of flat cam-elements 29 of a feed-roll-release rock-shaft 30, mounted below the rod 24 and having a crank-arm 30^a connected by link 31 to a feed-roll-release lever 32.

In one use of the typewriting machine embodying the present invention, a record-sheet 34 is inserted over the paper-table 20 around the platen 11, and its first line of writing gaged to the printing line in a way to presently appear, and may be held against the platen at the delivery side by paper-fingers 35 mounted on a paper-finger rod 36 and carrying pressure-rolls 37. The record-sheet may be line-spaced around the platen by means of finger-wheels 38 or line-spacing instrumentalities, not shown, which engage a ratchet-wheel 39 fast on the platen-shaft 12. The parts mentioned hereinbefore may be the same as in an Underwood billing typewriting machine, except as hereinafter noted.

For convenience in inserting and collating a statement-sheet 40 and an underlying carbon-sheet 41 at the front of the platen with respect to the record-sheet 34, a front paper or collating table, generally designated as 42, has integral rearwardly-extending legs 43 pivoted on inreaching studs 44 in the side bars 16 of the carriage. These studs may also serve to hold usual stops 44^a which arrest the upward movement of the platen-shift-frame and may be threaded in the usual tapped holes for fastening the stops to the carriage. To fasten the table 42 against lateral movement relative to the carriage, while permitting lateral adjustment for a purpose to presently appear, a collar 45 may be fastened by a set-screw 46 on each stud 44 and be disposed against the outer face of the adjacent leg 43. There is provided in the table 42 two elongated parallel slots 47 whose axes lie in planes that intersect at right angles the axis of the pivoted table 42. Two brackets 48, each having an inverted V-shape, are fastened to the front carriage-rail 17 by screws 49 and support a plate or bar 50 in which are fastened two gage-pins 51 spaced apart the same distance as the slots 47, and are positioned so that, when the front paper-table 42 is swung to its extreme forward position, the pins will project upwardly through the slots 47. To provide for adjustably moving the pins toward or away from the platen, 130

the plate 50 is fastened by screws 52 which pass through elongated slots 53 in said plate 50 to be threaded in tapped holes in the brackets 48.

5 For inserting the statement-sheet 40 and its underlying carbon-sheet 41 at the front of the platen, the work-face of the paper-table 42 is held in operative position slightly above the tops of the pins 51 (Figure 3) by a cushioning leaf-spring 54 fastened by screws at the center portion of the spring to the opposite side of the table from its work-face. The spring has both ends bent away from the table 42 for yielding engagement against the plate 50. In the work-sheet feeding position 10 of the paper-table, the plane of its work-face is forwardly inclined a large angular degree from a vertical plane to be disposed in a convenient position for manipulating work-sheets thereon, and a forwardly-extending finger-rest or shelf 55 is then disposed substantially horizontally.

While the paper-table 42 is in its work-sheet feeding position, the plane of its work-face intersects the upper end of the type-guide 19 and intersects the platen below the printing line. The lower portion of the table 42 is disposed in the paths of the types 10. To enable a work-sheet to be fed over the table without colliding with the type-guide, it is a feature of my invention to move the carriage rightwardly to the end of its travel and provide means at the right of the printing point for guiding the statement-sheet behind the apron 21 after the sheet leaves the table. To this end, a sheet-metal deflector-plate 56 is preferably mounted at the right of the type-guide 19, and has a portion 57 curved parallel with the periphery 40 of the platen and disposed closely adjacent thereto, and extends downwardly from adjacent the printing line to within close proximity of the top of the apron 21. A horizontal flange 58, integral with the curved portions 57, extends forwardly beyond the rear or inner edge of the table 42 when the latter is in its forward position. The top of the flange may be used for gaging the record-sheet to typing position. A depending ear 59 at the left end of the deflector-plate is fastened to the segment 18, and a depending ear 60, intermediate the ends of the deflector-plate, is fastened to a bracket 61 mounted on the adjacent main frame-member 18^a.

55 After the statement-sheet has been passed rearwardly around the platen, the table 42 will be pressed down against the spring 54 to bring the tops of the gaging pins 51 to effective gaging position above the work-face 60 of the table, and the leading edge of the statement-sheet will be gaged against the pins, and its right edge gaged against a side-edge gage in the form of an angle-plate 62, which may be riveted on the table 42 and have an up-right flange 63 transversely disposed to the

table 42. The inner or lower end of the flange 63 is concavely tapered to have a slightly larger radius than the platen and the tapered portion is positioned to be disposed parallel to and within close proximity to the periphery of the platen upon swinging the paper-table to its rearmost position. It can be readily seen that the side-edge gage may be made laterally adjustable, if desired, without adversely affecting any advantage 75ous feature of the present invention.

It is usual, in inserting work-pieces at the front of the revoluble platen 11, to release the feed-rolls, as is illustrated in Figure 3. It is therefore also a feature of the present 80 invention to provide an operative connection between the pivotally-mounted paper-table 42 and the feed-rolls 22 and 23, whereby swinging the table forwardly to work-sheet feeding position will automatically release 85 the feed-rolls, and swinging the table to its rearmost position will first cause the feed-rolls to be moved to normal effective position 90 and thereafter to be disconnected from the table 42, but still connected with the usual feed-roll release-lever to be operated at will by the latter independently of the table. To this end, a stud-screw 65, having a reduced end portion 66, passes loosely through a hole 95 in the lower end of the link 31 and is threaded into a tapped hole in the end of the crank-arm 30^a, the reduced portion extending inwardly a short distance past the arm. The right-hand leg 43 of the table 42 is provided 100 with an angular integral rearward extension 67, which may have an inverted V-shaped form, and which may include a forward member 68 and a rear member 69 of the extension (see Figure 3). The rear end of the member 69 has a short, integral, inreaching 105 lug 70 which is arranged for engaging against the rear side of a link 71, whose upper end is pivotally fastened on a pin 72 fast in the extension 67. The lower end of the link 71 has a rearwardly-opening, upwardly-inclined 110 notch 73. A light tensile spring 74 has its rear end fastened to a pin 75 in the platen-frame 14 and its front end to the link 71 a short distance below the pin 72. After the statement-sheet 40 has been gaged on the 115 table 42, and the latter swung to its rearmost position, the link 71 and the screw-portion 66 are disposed in the position illustrated in Figure 4. In this position, the weight of the table 42 acting downwardly about the pivot-studs 44 is sufficient to overcome the force 120 of the light spring 74, which tends to swing the table clockwise by pulling the link 71 against the lug 70.

Upon initial forward movement of the 125 table 42, to position it for removing a typed statement-sheet and inserting a new one, the lug 70 and link 71 are swung upwardly, and, at the same time, the link is pulled rearwardly by the spring 74. The joint action of the 130

pin 72 and lug 70, coacting with the spring 74, is effective to cause the notch 73 to be moved into engagement with the reaching screw-portion 66. Further forward movement of the table 42 to its work-sheet-feeding position, causes the link 71 to rise and swing the crank-arm 30^a and rock-shaft 30 counterclockwise, which is effective to release the feed-rolls 22 and 23.

When a typed statement-sheet has been removed and a new one is inserted and gaged, as described above, the operative, while gripping the new statement-sheet 40 and carbon-sheet 41 against the table 42 with one hand, as illustrated in the dot-and-dash representation of the table in Figure 3, will move with her other hand the table rearwardly. This movement is effective to swing downwardly the link 71, whose notched lower end is held by the spring in engagement with the screw-portion 66, and is thereby effective for rotating the rock-shaft 30 clockwise and permitting the spring-pressed feed-rolls to be moved to grip the statement-sheet against the platen before the sheet is released from the grip of the operative's hand on the table 42. A further continuous rearward movement of the table 42 swings the link 71 downwardly an additional amount, and the upwardly-inclined notch 73 rides off the screw-portion 66. Upon further continuous movement of the table to its extreme rearward position, which is determined by a lateral pin 77 in an upright integral ear 78 on the right side of the table 42 striking a usual top flange-member 79 of the platen-frame 14, the link 71 is swung to the Figure 4 position by the lug 70. In the last-named position of the notched link 71, the latter will not interfere in any way with the control of the feed-rolls by operation of the usual feed-roll release-lever, which arrangement is desirable for adjusting the record-sheet to the printing line of the platen, a better view of the printing line being had when the table 42 is in its rear-most position.

It is desirable to provide that in any position it may be disposed, the link 71, which is supported on the laterally-movable carriage 15, will not strike against the fixed deflector-plate 56, which is disposed closely adjacent the platen. To this end, the link 71 does not extend in a straight line from the screw-portion 66 to the pin 72, but is bent rearwardly at 80 (Figure 3). It can be readily seen that the rear extension 67 of the right leg 43 and the link 71 may have different forms from those illustrated in the drawings without departing from the scope of my invention.

The pressure-rolls 37 are effective for holding the record-sheet 34 against displacement on the platen when the lower feed-rolls are released. Since the pressure-rolls are preferably disposed adjacent the side edges of the record-sheet, which is usually considera-

bly wider than the statement-sheet, it is desirable to have means for holding the leading end portion of the statement-sheet 40 against the platen above the printing line to assure good typing impressions and to keep the statement-sheet from falling forwardly. To this end, the paper-table 42, while in its rearmost position, is held by engagement of the pin 77 on the platen-frame in a position which brings the work-face of the paper-table slightly above the platen in a plane substantially tangent thereto with the lower edge of the table positioned a short distance above the printing line, approximately in line with the lower edges of the pressure-rolls 37, which engage in rectangular notches or cut-outs 81 in the lower edge of the table 42. The notches are made extra wide to permit lateral adjustment of the paper-table and insure that the slots 47 engage accurately around the pins 51. Since the paper-table may be inexpensively formed almost entirely from one piece of sheet-metal, it is usually preferred to have a separate table for each width of statement-sheet.

It will be noted from inspection of Figure 5, that when the carriage 15 is centered on the machine, the deflector-plate 56 extends past the right-hand side-bar 16 of the carriage a considerable distance. The free lateral movement of the carriage is not hindered by this construction of the deflector-plate, however, since the top edge of the latter is low enough to clear the bottom edge of the adjacent side-bar 16 (Figure 4). By proper adjustment of the usual carriage-stops (not shown), the platen 11 may be moved laterally alongside the right end portion of the deflector-plate 56, when desired, for inserting a wide statement-sheet at the front of the platen without colliding with the type-guide 19.

Variations may be resorted to within the scope of the invention, and portions of the improvements may be used without others.

Having thus described my invention, I claim:

1. In a typewriting machine having a type-guide, the combination with a carriage having a front rail, a revoluble platen around which a record-sheet may be fed, lower feed-rolls engaging said platen, and upper pressure-rolls engaging the side edges of said record-sheet, of two upwardly-extending gage-pins supported by said rail, a work-sheet deflector-plate fixed at the front of said platen below the printing line and to one side of said type-guide, a paper-table pivotally mounted on said carriage for movement to one side of said type-guide and yieldingly supported by said front rail in a position inclined downwardly toward said plate for co-operating with the same for inserting a work-sheet at the front of said platen without fouling said type-guide; said table

- having slots positioned for engaging about said pins upon being swung forwardly from said sheet-inserting position whereupon said pins protrude through the slots in said table 5 to be effective for gaging said work-sheet relative to the printing line, and an operative connection to enable said table to release said feed-rolls when said table is moved to its work-sheet-inserting position, and to enable 10 said table to restore said feed-rolls upon swinging said table rearwardly; said table being effective in its rear position for retaining said work-sheet against the platen.
2. In a typewriting machine, the combination with a carriage having a front rail and a platen, of a plurality of upwardly-extending gage-pins supported by said front rail, and a slotted paper-table pivotally mounted on said carriage between said platen 15 and said front rail, and arranged to be supported by said front rail in a downwardly-inclined work-sheet-inserting position, said paper-table being swingable from its work-sheet-inserting position to a work-sheet-gaging position, to permit said gage-pins to protrude through the slots of said table for gaging said work-sheet to typing position, said table being effective when adjacent said platen to retain said work sheet against said 20 platen.
3. In a front-strike typewriting machine, a platen, types for striking thereagainst, and a work-sheet-carrier in the form of a collating table incumbent position extending 25 forwardly from the front of said platen in position for having a work-sheet collated face down thereon and guided thereby down in front of said platen, the rear edge of said table extending downwardly and rearwardly 30 adjacent the front of said platen while said table lies in its work-sheet-collating forward position, said table being pivoted at its rear to swing upwardly and rearwardly to carry the work-sheet upwardly and rearwardly 35 with its back against said platen, preparatory to typing.
4. In a front-strike typewriting machine, a platen, types for striking thereagainst, a work-sheet-guiding apron disposed adjacent 40 said platen below the printing line thereof, a work-sheet-carrier in the form of a paper-table pivotally mounted at the front of said platen to be disposed in a forwardly-inclined position for having a work-sheet positioned 45 thereon and inserted downwardly at the front of said platen, the lower edge of said table extending downwardly adjacent said platen, and a fixed deflector-plate having a portion curving around said platen and extending from a point adjacent the top of said apron upwardly to a point adjacent said printing line and a short distance below the lower edge of said table, for co-operation 50 with the table when the latter is disposed in its work-sheet-inserting position, said table 55 being mounted for swinging rearwardly to position above the printing line to carry said work-sheet against said platen.
5. In a typewriting machine, a carriage, a platen, a paper-table pivotally mounted on said carriage at the front of said platen to be disposed in a forwardly-inclined position for having a work-sheet positioned thereon and inserted at the front of said platen, and gaging instrumentalities supported on said carriage independently of said table to co-operate with the latter in positioning said work-sheet in typing position, said table being effective, upon being swung rearwardly after said work-sheet has been 60 gaged, to conduct the leading end of the work-sheet rearwardly at the delivery side of the platen.
6. In a typewriting machine, a carriage having a front rail, a platen, a slotted paper-table pivotally mounted at the front of said platen to be disposed in a forwardly-inclined position for having a work-sheet positioned thereon and inserted at the front of said platen, the lower edge of said paper-table being disposed away from said platen, and two gage-pins carried by said rail to project upwardly through the slots in said table for gaging the first writing line of said work-sheet relative to the printing line of said platen, said table upon being swung to its rearmost position being effective for moving said first writing line against said platen at said printing line preparatory to typing said work-sheet, said lower edge being disposed 65 above said printing line.
7. In a typewriting machine, the combination with a carriage, a platen and lower feed-rolls engaging against the bottom of said platen, of a cumbent sheet-collating table upon which the sheet is placed in inverted position, said table pivoted on said carriage and extending forwardly from the platen and inclined downwardly and rearwardly toward the platen at the printing line to form a throat for downward insertion of an inverted work-sheet bottom first at the front of the platen, instrumentalities operatively connecting said table to said feed-rolls, whereby the latter are caused to be released when said table is moved to its cumbent work-sheet-receiving position, said table movable away from the sheet-receiving position, to restore the rolls and carry the sheet back with its rear face against the platen.
8. In a typewriting machine, the combination with a carriage, a platen, and lower feed-rolls engaging said platen, of a slotted paper-table pivoted on said carriage forwardly from said platen and inclined forwardly and upwardly for having inserted over its upper surface a work-sheet at the front of the platen, gage-pins supported on said carriage and arranged for projecting through the slots in said table for gaging said work-sheet 120

upon moving said table from its work-sheet-inserting position, and instrumentalities connecting said table to said feed-rolls effective to cause the latter to be released when said table is disposed in its work-sheet-feeding 5 or work-sheet-gaging position.

9. In a typewriting machine, the combination with a carriage having a front rail, a platen, and lower feed-rolls engaging said platen, of a slotted paper-table pivoted on said carriage forwardly from said platen and inclined forwardly and upwardly in a position slightly to the rear of its extreme forward position for having inserted over its 10 upper surface a work-sheet at the front of said platen, gage-pins supported on said front carriage-rail arranged for projecting upwardly through the slots in said paper-table when the latter is in its extreme forward position, said gage-pins being effective 15 for gaging the first writing line of said work-sheet to typing position, and instrumentalities connecting said table to said feed-rolls effective to cause the latter to be released 20 when said paper-table is disposed in its work-sheet-feeding or work-sheet-gaging position.

10. In a typewriting machine having a fixed type-guide, in combination, a laterally movable carriage, a revoluble platen in said carriage, an apron disposed adjacent the lower side of said platen effective for guiding a work-sheet inserted at the front of said platen rearwardly therearound, a fixed deflector-plate at the front of said platen 25 extending from the top edge of said apron upwardly adjacent the printing line, and a paper-table supported on said carriage and inclined downwardly and rearwardly toward said deflector-plate, said plate being positioned on the right side of said type-guide and having at length substantially equal to the length of said platen, said plate being effective for co-operation with said apron and said table for inserting a wide work-sheet 30 rearwardly around said platen upon moving said platen alongside said deflector-plate without colliding with said type-guide.

11. In a typewriting machine, the combination with a platen and a carriage having 35 a front rail, of a slotted paper-table pivotally mounted on the sides of said carriage between said platen and said front rail for inserting a work-sheet at the front of said platen, a lateral bar supported by said front rail to the rear thereof to engage under said table, and two upwardly-projecting pins in said bar positioned for protruding through the slots in said table upon swinging the latter forwardly 40 from its work-sheet-inserting position, said pins being effective thereupon for gaging said work-sheet to typing position.

12. In a typewriting machine, the combination with a platen and a carriage having a front rail, of a plane, slotted paper-table 45 pivotally mounted on the sides of said car-

riage between said platen and said front rail for inserting a work-sheet at the front of said platen, a lateral bar supported by said front rail to the rear thereof to be disposed under the forward portion of said table, a leaf-spring on the forward side of said table effective for engaging against said bar and yieldingly holding said table in work-sheet-inserting position, and two projecting pins in said bar positioned for protruding through the 50 slots in said table upon pressing the latter against the action of said spring forwardly and downwardly from its work-sheet-inserting position for gaging said work-sheet to typing position.

13. In a typewriting machine, the combination with a platen and a carriage having a front rail, of a plane paper-table pivotally mounted on the sides of said carriage between said platen and said front rail and provided with elongated slots transversely disposed to the axis of said table, a lateral bar fastened on the rear side of said front rail effective to engage under said table, a leaf-spring fast on the forward side of said table effective for engaging said bar and yieldingly supporting said table in a forwardly-inclined position for inserting a work-sheet therefrom at the front of the platen, upwardly-projecting pins fast in said bar positioned for protruding through the slots in said table upon pressing the latter downwardly against said yielding spring, said pins thereupon becoming effective for gaging said work-sheet to typing position, and means for adjusting said pins toward or away from the platen. 90

14. In a typewriting machine, the combination with a platen and a carriage having a front rail, of a paper-table pivotally mounted on the sides of said carriage between said platen and said front rail and provided with elongated slots transversely disposed to the axis of the pivots of said table, means for laterally adjusting said table, said paper-table being effective for inserting a work-sheet at the front of said platen, a lateral bar fastened on said front rail to the rear thereof for adjustment toward and away from the platen, said bar being positioned to engage under the free end of said table and to support the latter in a forwardly-inclined work-sheet-inserting position, upwardly-projecting gage-pins fast on said bar positioned for protruding through the slots in said table, and a side edge gage on said table mounted for co-operation with said gage-pins for positioning said work-sheet on said table relative to the printing point. 110

15. In a typewriting machine, the combination with a platen and a carriage having a front rail, of a paper-table pivotally mounted on the sides of said carriage between said platen and said front rail and provided with elongated slots transversely disposed to the axis of the pivots of said table, 125

- means for laterally adjusting said table, said paper-table being effective for inserting a work-sheet at the front of said platen, a lateral bar fastened on said front rail to the 5 rear thereof for adjustment toward and away from the platen, said bar being positioned to engage under the free end of said table and to support the latter in a forwardly-inclined work-sheet-inserting position, up- 10 wardly-protruding gage-pins fast on said bar positioned for protruding through the slots in said table, and a side edge gage on said table mounted for co-operation with said gage-pins for positioning said work-sheet on 15 said table relative to the printing point, said side edge gage including an upwardly-extending flange mounted on the work-face of said table at right angles to the line of said pins, said flange having a concavely tapered 20 inner end, the radius of the concave end portion being slightly larger than the radius of said platen, said flange being positioned so that, upon swinging said table rearwardly about its pivot, said concave end portion will 25 engage the convex periphery of said platen and permit said table to be disposed closely adjacent said platen for conducting said work-sheet rearwardly.
16. In a typewriting machine, the combination with a carriage and a platen, of a paper-table pivotally mounted on said carriage for movement to position at the printing line for inserting a work-sheet downwardly bottom first at the front of the platen, 30 and also to a second position for gaging said work-sheet to typing position, and also to a third position to carry said work-sheet facewise rearwardly against the platen, and normally ineffective gaging means rendered effective by the movement of said table to said 35 second position.
17. In a typewriting machine, the combination with a carriage and a platen, of a paper-table pivotally mounted on said carriage and yieldingly supported in a forwardly-inclined position for inserting a work-sheet downwardly at the front of the platen, said paper-table being movable forwardly from said work-sheet-inserting position to a 40 work-sheet-gaging position, and sheet-gages rendered effective by the last-mentioned movement of said table, and said paper-table being swingable rearwardly adjacent said platen to conduct said work-sheet rearwardly 45 facewise to the delivery side of said platen.
18. The structure described in claim 5, having lower feed-rolls engaging the platen, and an operative connection between said feed-rolls and the pivoted paper-table effective to 50 cause said feed-rolls to be released when said paper-table is moved to its work-sheet-inserting position.
19. In a typewriting machine having a platen, lower feed-rolls and a feed-roll-release lever, the combination of a sheet-car- 55
- rier in the form of a pivoted paper-assembling cumbent table adjacent the printing line on the platen and extending forwardly from the platen, for inserting a work-sheet face down and bottom edge first at the front of said platen, said table movable to carry the leading end portion of the introduced work-sheet rearwardly with its back face against the platen, and means connecting said pivoted paper-table to said feed-rolls, for releasing said feed-rolls when said table is moved to its work-sheet-inserting position, and for restoring said feed-rolls when said table is moved to carry said introduced work-sheet facewise rearwardly to the platen, said connecting means effective to leave said feed-rolls disconnected from said table in said last-named position, whereby said feed-rolls may be controlled by said release-lever independently of said table for adjusting said work-sheet upon displacement thereof. 60
20. In a typewriting machine having a type-guide, a revoluble platen, an apron at the front of said platen below the printing line effective for guiding a work-sheet rearwardly under the platen, and a fixed deflector-plate at the front of said platen extending upwardly along the periphery of the platen from the upper edge of said apron to within a short distance of the printing point, said deflector-plate being positioned on the right and said type-guide and extending therefrom rightwardly a distance substantially equal to the length of said platen, for guiding a wide work-sheet between said apron and said platen when the latter is disposed substantially at the end of its rightward travel, whereby a work-sheet is prevented from colliding with said type-guide. 65
